UNITED STATES PATENT OFFICE

145,324

DESIGN FOR A CHILD'S VEHICLE

Jack N. O'Connor and Stella M. O'Connor,
Los Angeles, Calif.

Application October 3, 1945, Serial No. 122,494

Term of patent 14 years

(Cl. D34—15)

To all whom it may concern:

Be it known that we, Jack N. O'Connor and Stella M. O'Connor, citizens of the United States and residents of Los Angeles, county of Los Angeles, State of California, have invented a new, original, and ornamental Design for a Child's Vehicle, of which the following is a specification, reference being had to the accompanying drawings, forming part thereof.

We claim:

The ornamental design for a child's vehicle, as shown.

JACK N. O'CONNOR.
STELLA M. O'CONNOR.
